United States Patent Office.

J. C. STODDARD, OF WORCESTER, MASSACHUSETTS.

Letters Patent No. 100,950, dated March 15, 1870.

IMPROVEMENT IN HORSE-RAKES.

The Schedule referred to in these Letters Patent and making part of the same.

To all whom it may concern:

Be it known that I, J. C. STODDARD, of Worcester, in the county of Worcester, and State of Massachusetts, have invented a new and improved Horse-Rake; and I do hereby declare that the following is a full, clear, and exact description of the same, reference being had to the accompanying drawings and to the letters of reference marked thereon making a part of this specification.

This invention relates to a new and useful improvement in horse-rakes of that class which are provided with wire teeth; and

It consists in a novel way of attaching the teeth to the rake-head or bar, as hereafter fully shown and described, whereby the teeth may be readily attached to and detached from the said head or bar, without loosening any nuts or fixtures thereon, and the teeth rendered capable of being adjusted relatively with each other and the rake-head or bar with the greatest facility.

The invention also consists in a novel application of springs to the teeth, as hereinafter fully shown and set forth, whereby the teeth are kept to a proper working position, and allowed to yield or give, to conform to any inequalities of surface over which they may pass, and at the same time be properly supported and prevented from having any lateral play or movement.

In the accompanying sheet of drawings—

Figure 1 is a plan or top view of my invention;

Figure 2, a detached plan or top view of a portion of the same;

Figure 3, a side view; and

Figure 4, a rear view of the same.

Similar letters of reference indicate corresponding parts in the several figures.

To enable those skilled in the art to fully understand and construct my invention, I will proceed to describe it.

A represents a portion of the rake-head or bar, to which the teeth are attached; and

B represents one of a series of cast-metal heads or stocks, which are secured to the rake-head or bar A, each by two bolts *a a*, one near each end.

These heads or stocks are cast with a horizontal cylindrical portion, *b*, which is a little elevated above the base *c*, and provided at each end with a flange, *d*, and a cross-bar or guard, *e*, connecting the two flanges at about the centers of their front edges.

At the rear end of the base *c* there is an upright plate, *f*, which is provided with a right-angular slot or opening, *g g'*, as shown clearly in fig. 4.

D is a rake-tooth, constructed of a piece of round steel wire, curved, as shown in fig. 3, and having its upper end bent in the form of a semicircle or hook,

h, to fit around the cylindrical portion *b* of the head, between it and the cross-bar or guard *e*, said hook extending around a little more than half the circumference of *b*.

E is a spring, which is also made of a piece of steel wire of the same, or about the same diameter as the tooth, and having its upper part of cylindrical form, and bent in hook-shape, as shown at *h'*, to fit around the cylindrical portion *b* of the head *B*, in the same way as the tooth, and directly by the side of it.

I desire to direct especial attention to this feature, the angular slot *g g'*, in the part *f*. It will be seen, upon inspection of the drawings, that the spring *F* and tooth *D* lock each other securely in place in the horizontal portion of the slot, entirely preventing lateral movement, and at the same time permitting the ready attachment and detachment of the teeth.

The lower part of this spring may be flattened, and it is bent or curved so as to catch or hook over the tooth at any proper distance from the upper end of the latter, as shown at *i*.

The hooks *h h'* of the tooth and spring, fill the space on *b*, between its two flanges *d d*.

The spring *E* is fitted or passes through the horizontal part *g* of the slot or opening in the upright plate *f*, and the tooth *D* is fitted or passes through the vertical part *g* of said slot or opening.

The tooth, it will be seen, is allowed to rise and fall in the part *g* of the slot or opening, but the spring *E* cannot rise in the part *g'*, and, consequently, the latter keeps the tooth down to its work, but allows it to yield or give to any inequalities of surface over which it may pass.

This spring may, if necessary, have one or more convolutions or coils to increase its elasticity. I do not confine myself to any particular shape for said spring.

All the parts above described as comprising the cast-metal head *B* are cast in one piece, the base *c* is secured to the rake-head by the bolts *a a* passing entirely through it, the holes *j* in the base being considerably larger in diameter than the bolts, to admit of a certain degree of adjustment of the head *B* in securing it to the rake-head or bar *C*.

By this arrangement it will be seen that the teeth may be secured to the rake-head or bar *C*, with the greatest facility, and all at a proper and equal distance apart, and parallel with each other; and, in case a tooth should be required to be detached and replaced by a new one, all that is necessary to be done in order to effect that is to slip its spring *E* off from it, and raise the tooth until its hook *h* may be slipped off from the cylindrical portion *b* of the head, the new tooth may then be readily attached, and the spring adjusted over it.

The spring and tooth being fitted in and attached to the same head B, in adjusting one the other is similarly adjusted at the same time. This is a great advantage over the old mode of attaching rake-teeth, where the teeth and springs are secured to separate bars or parts, which require to be adjusted separately whenever the position of the teeth requires to be adjusted, and which also have separate supporting-frames for the teeth.

I am aware that it is not new to form a hook at the inner end of the tooth of a horse hay-rake, but so far as I know, it has heretofore been always necessary to remove the bolt over which the tooth is hooked, when it is desired to change the tooth.

Having thus described my invention,

What I claim as new, and desire to secure by Letters Patent, is—

1. The head B, provided with a cylindrical portion, b, and a projecting portion, f, having a right-angular slot or opening, g g', through which the tooth and spring pass, substantially as shown and described.

2. The combination of the tooth D and spring E, with the cylindrical portion b and slot g g', all constructed and arranged substantially as herein set forth.

J. C. STODDARD.
